UNITED STATES PATENT OFFICE.

MARTIN BELVILLE, OF SAN FRANCISCO, CALIFORNIA, ASSIGNOR TO THE BELVILLE MANUFACTURING CO., INC., OF SAN FRANCISCO, CALIFORNIA, A CORPORATION OF CALIFORNIA.

SHOE-POLISHING MACHINE.

Application filed January 14, 1920. Serial No. 351,400.

To all whom it may concern:

Be it known that I, MARTIN BELVILLE, a citizen of the United States, residing at San Francisco, in the county of San Francisco and State of California, have invented 5 new and useful Improvements in Shoe-Polishing Machines, of which the following is a specification.

This invention relates to shoe polishing 10 machines.

The objects are to provide a machine which will operate to clean, apply blacking to, and polish shoes in successive operations while they are upon the feet of the wearer, 15 which is automatic in its operation, which will operate upon all parts of the shoes under treatment, which, while operating to polish the uppers of high shoes, may be used to operate upon low shoes without injury to 20 the hosiery of the wearer and which will stop automatically when its cycle of operation has been completed. A further object is to provide a shoe polishing machine having foot rests capable of vertical movement 25 so that the shoes may be presented in proper position to the brushes so that all parts of the shoes may be cleaned and polished.

With these and other objects in view, my 30 invention consists in certain features of structure, combination and relation which will be more fully set forth hereinafter.

I have illustrated one embodiment of my invention in the accompanying drawings, wherein:

35 Figure 1 is a plan view of my improved apparatus, certain parts being omitted in order to simplify the illustration;

Figure 2 is a side elevation, the driving motor being omitted, and certain parts being broken away or shown in section;

40 Figure 3 is a section taken substantially on the line 3—3, Fig. 1;

Figure 4 is a side elevation partly in section, of one of the polishing sets;

45 Figure 5 is a detail of the mechanism for placing the brushes of one set in operative position;

Figure 6 is a longitudinal vertical section through the rotating mechanism for the 50 brush holder;

Figure 7 is a section taken substantially on the line 7—7, Fig. 6;

Figure 8 is a perspective view of a part of the rotating mechanism illustrated in Figure 5;

Figure 9 is a section through the liquid container;

Figure 10 is a front elevation of the liquid container or dauber;

Figure 11 is a side elevation of one of the 60 foot rests;

Figure 12 is a detail, partly in section, of one of the foot rests;

Figure 13 is a side elevation of the actuating 65 mechanism for the brush holder rotating means and the electrical circuit-breaker;

Figure 14 is a detail of the ratchet wheel and pawl which actuates the circuit-breaker;

Figure 15 is a detail of a portion of one of the brush members and the brush-operat- 70 ing rod;

Figure 16 is a detail of one of the brush members.

Fig. 17 is a plan view, looking substantially from the line 17—17, Fig. 2, of 75 the means for locking the reciprocating mechanism during the changing of the polishing elements;

Fig. 18 is a section taken substantially on the line 18—18, Figs. 1 and 17.

Fig. 19 is a section taken substantially on the line 19—19, Figs. 1 and 2.

Referring to the drawings, wherein similar numerals denote like parts throughout the several views:

1 (see Figs. 1, 2 and 3) denotes a gear wheel which is driven by any suitable means, an electric motor 2 and driving pinion 3 being preferred. This gear 1 is fixed to a shaft 4 journaled in uprights 100 and carrying fixed pinions 5 and 6. The drive is taken from gear wheel 1 by a pinion 7 meshing with gear wheel 1 and mounted on a shaft 101 supported by uprights 102, said shaft carrying also a fixed gear wheel 8. A 90

square shaft 9 is mounted in brackets 10 and 104 and this shaft carries a sliding gear 11 which is adapted to mesh with gear wheel 8. The pinion 6 which turns with the gear wheel 1 meshes with a gear 12 rotatably mounted on a stud projecting from one of the uprights 100, said gear carrying a crank arm 13. This crank arm is connected to and oscillates a lever 14 through the medium of a link 15, the lever 14 being pivoted at 16 105 to a suitable standard 17. A shifting arm 18 is also pivoted at one end to lever 14, this shifting arm being provided at its opposite end with a slot through which projects a pin 19 carried by one arm of an 110

elbow lever 20 pivoted at 21 to a cross-member 103, connecting the brackets 10. The other arm of the elbow lever 20 is bifurcated, and the forked portions thereof embrace the 5 reduced base portion of the gear shifting device 22 which is adapted to slide in a slot formed in a second cross-member 23 connecting the brackets 10. This gear shifting device has projecting arms 24 which embrace 10 the sliding gear 11 and move the same longitudinally on the shaft 9 when the elbow lever 20 is oscillated.

Crank 25 formed at the ends of the square shaft 9 are connected by links 26 with arms 15 27 formed at the ends of aligned square shafts 28 journaled in uprights 105. Bifurcated levers 29 are formed with hubs 290 slidably mounted on the shafts 28, the forked portions of these levers being provided with 20 slots 30.

The polishing sets are slidably mounted on transverse rods or cross-members 31 supported by uprights 106. Each set comprises a pair of slides 32 guided respectively on 25 the rods 31 and on which a brush-holding member (designated as a whole in Figs. 1 and 2 by the numeral 33) is rotatably mounted by means of a reciprocating rod 34. This rod (see also Figs. 4, 5 and 6) projects 30 through the ends of the corresponding brush-holding member and through brackets or upright portions 107 on the corresponding slides 32, one end of the rod being pivoted to one of the bifurcated levers 29 through 35 means of which the rod is reciprocated (Fig. 1). Each brush-holding member 33 comprises a pair of end heads 108 (Fig. 4) connected by a plurality of side bars 35 on which the back portions 36 of the several 40 brushes of the set are slidably mounted, respectively. These brush back portions have lugs 37 formed on their inner sides, which lugs are adapted to be selectively engaged by an engaging member 38 preferably in the 45 form of a yoke and rigidly secured to or formed integral with the corresponding reciprocating rod 34.

In a machine constructed in accordance with my invention I usually provide four 50 polishing elements, namely, a dauber and three brushes all of which are substantially similar in structure, one brush being adapted to clean the shoes, the dauber to apply blacking or other polish thereto, the second 55 brush to operate upon the shoes after the blacking has been applied, and the third brush, which is preferably faced with a cloth, to complete the polishing operation. Each of these elements comprises a central 60 member 39 to which the back portion 36 is secured and hinged to which are two end members 40 (each of which may, in turn, comprise a plurality of hinged sections) and a top member 41. Springs 42 (Figs. 1, 2, 4, 65 and 16) tend to press the end and top mem-

bers, respectively, inward, thus ensuring, when the element is reciprocated, that all parts of the shoe will be reached. The blacking is applied to the shoe in the second operation, after one of the brushes has completed its function, and for this purpose I provide a dauber in the form of a container 43 (Fig. 9), which is somewhat similar in outline to the brush members, and which comprises a central compartment 44 (Figs. 75 4 and 10), two hinged end compartments 45, and a hinged upper compartment 46, which subsidiary compartments, like the brushes, are forced inward by the action of springs. The edges of the container compartments 80 are turned inward and serrated, as indicated at 47, for the purpose of holding the sponge portions 48 in position in the containers. Each brush holder 33 is rotated and the elements thereon brought successively into 85 operative position by means of a ratchet wheel 49, which is keyed or otherwise fixed to a sleeve 64 (Figs. 6 and 7) projecting from one of the end heads 108, and a pawl 50, which is pivoted to a lever 51 having a 90 hub loosely mounted on the sleeve 64. The outer end of the lever 51 is connected by a link 52 with a pin 52^a projecting from an arm 67 (see also Fig. 5) pivoted at 68 to the corresponding slide 32. The pin 52^a is 95 also connected by a short link 109 (Figs. 1, 2 and 18) with an arm 53 having a hub 110 (Fig. 1) slidably mounted on a squared shaft 54 journaled in uprights 119. The shaft 54 is oscillated by means of a link 55 100 pivoted to a crank arm 56 fixed to said shaft, which link is pivoted, as indicated at 57 (Figs. 1 and 13) to a lever 58 pivoted to an upright 111. The lever 58 is oscillated from a pinion 59 rotatably mounted on a stud projecting from one of the uprights 100, said pinion having a crank arm 60 connected with the lever 58 by a link 61. The pinion 59 meshes with the pinion 5 secured to the shaft of the drive wheel, so that rotation of the 105 drive wheel will cause intermittent movement of the ratchet wheel 49, thereby intermittently rotating the brush holder 33 and bringing the brushes successively into operative position.

In their normal or inoperative positions the polishing elements are centrally located on the side bars 35, the lugs 37 of said elements being disposed substantially at the longitudinal centers of said bars. The arrangement is such that when each polishing set is rotated, the yoke or engaging member 38 on the corresponding rod 34 is substantially opposite the lugs 37 of the several 110 polishing elements of the set so as to engage 115 the lug 37 of the polishing element next moved to operative position.

In order to lock the rods 34 against longitudinal movement and accurately position them with their engaging members 38 op- 120 125 130

posite the lugs 37 of the polishing elements, when the polishing sets are rotated, there is provided a forked locking member 127 (see particularly Figs. 17 and 18) which is slidably mounted for vertical movement in an upright 126 and adapted, when elevated, and when the corresponding arm 29 is in its central upright position, as shown in Fig. 18, to engage the squared hub 290 of said arm 29 and lock said arm, thereby holding the mechanism for reciprocating the rods 34 against operation and locking said rods in their central positions. The locking member 127 is operated by a bell-crank lever 125 pivoted to the upright 126 and carrying a pin 124 co-operating with the slotted end of a link 123 connected at its opposite end to one arm of a lever 121 pivoted at 122 to the base of the machine. The other arm of the lever 121 is connected by a link 120 (see also Fig. 2) with the lever 14, whereby when the latter lever is oscillated to shift the pinion 11 out of mesh with the gear 8 the locking member 127 will be elevated to lock the parts against movement, as above described.

In order to secure the brush holding members 33 against turning when the reciprocating rod is in operation, I provide for each polishing set a notched wheel 63 (Figs. 1, 2, 5 and 6) which is affixed to the sleeve 64 of the corresponding end head 108 and co-operates with a dog 65 pivoted to the upright portion 107 of the slide 32 of the holder. To this dog is pivoted a hook 66 which takes under the arm 67 which, as above explained, is connected by the link 52 to the ratchet operating lever 51. When the lever 51 is moved to turn the ratchet wheel 49, the dog 65 is removed from contact with the notches 40 of the notched wheel, thereby allowing the ratchet to turn freely, and when the ratchet pawl returns to its original position, the pawl 65 takes position in one of the notches 45 of the notched wheel and prevents any angular movement on the part of the brush holder or the brushes while the brushes are being reciprocated.

A ratchet wheel 70 is mounted on a shaft 113 journalled in a standard 112 (Figs. 1, 50 13 and 14) adjacent to the drive wheel. This ratchet wheel is operated by a pawl 71 on a pawl carrier 114 loosely mounted on the shaft 113 and connected by a link 72 with the lever 58. Fast on the shaft 113 is a 55 crank arm 73 to which is pivoted a connecting rod 74 having a slot in one end and adapted to be connected to the handle of a suitable electric switch 75. The ratchet wheel carries a suitable number of teeth so that when all of the polishing brushes have 60 functioned, a complete revolution of the ratchet wheel has been made and the electric circuit is broken through means of the switch 75.

Between each pair of polishing sets, I

provide a foot rest which consists of the base portion 76 (Figs. 11 and 12) which has an interior vertical channel 77 provided with a spiral spring 78 and a vertical channel 79 in one side face thereof. Positioned on the top of this base portion is the foot rest 80 which has a depending spindle 81 adapted to enter the interior channel 77. This spindle is provided with lugs 82 which are adapted to bear upon the top part of spiral spring 78 and maintain the foot rest in a relatively elevated position. The foot rest is provided on one side with a rack bar 83 extending substantially parallel to the depending spindle, which rack bar is adapted to enter the channel 79 in the side face of the base portion and to cooperate with a strip of spring metal 84 secured at one end to the base portion, the other end bearing upon the notches in the rack bar whereby the foot rest is firmly held when raised to any of the elevated positions. It is apparent from the structure provided that the shoe may assume position at various vertical levels. By the provision of these means it is possible for the person whose foot-wear is being treated to cooperate with the machine in securing the best results and thereby permitting the use of certain judgment and manual selection to collaborate with the mechanical functions of the machine.

To remove the polishing sets from operative position with respect to the foot rest, I provide (see Figs. 1, 2, 5 and 6) a shifting arrangement comprising the longitudinal 100 rock shafts 86 journalled in uprights 115 and having upstanding forked levers 87 adapted to take over the shafts 28, 31 and 54 and to bear upon the ends of the slides 32 and the hubs of the levers 29 and 53. These rock 105 shafts (see also Fig. 19) are provided with arms 116 connected by links 88 and yoke 117 with a bell crank lever 89 pivoted to the stand of the machine and connected by a connecting rod 90 with a hand lever 91. It is apparent that when the hand lever is pulled back the rock shafts 86 will be turned, forcing the forked levers 87 against the ends of the slides 32 and the hubs of the levers 29 and 53, thereby pushing the brushes with 115 their respective operating connections away from the foot rest and permitting the shoe to be removed. It is apparent that after the shoe has been removed the polishing sets will be returned to operative position by the 120 action of springs 92 on shafts 28, 31 and 54, respectively upon the hand lever 91 being returned to its forward position.

In the operation of my improved machine the feet are placed upon the rests provided, the brush shifting lever 91 is actuated and operates through the rod 90, bell crank lever 89, rods 88, rock shafts 86, and arms 87 to shift the brush sets to contact with the sides of the shoe, and the motor or other 130

prime mover is started in any suitable manner. Rotation of the main gear 1 is transmitted through the pinion 7, shaft 101, gear 8, pinion 11, and shaft 9 to the cranks 25 which, in turn, operate, through the connecting rods 26, arms 27 and shafts 28, to oscillate the arms 29 and thereby reciprocate the rods 34 and the polishing elements then in operative engagement therewith through the lugs 37 and yokes 38, the cleaning brushes being at this time in operative position. After a predetermined angular movement of the gear 1 (360° more or less depending upon the ratio of the gearing), the pinion 6, acting through the gear 12, arm 13, link 15, lever 14, and shifting arm 18, will rock the elbow lever 20 and move the pinion 11 along the shaft 9 out of mesh with the gear 8, thereby stopping the reciprocation of the rods 34 and polishing elements, said rods 34 being locked in their central positions by the elevation of the forked locking member 127, which is also actuated by the lever 14 through the link 120, lever 121, link 123, and bell-crank lever 125. At substantially the same time, or immediately thereafter, the pinion 5, acting through the gear 59, arm 60, link 61, lever 58, connecting rod 55, and arm 56, will rock the shaft 54 and arms 53, thereby, through the link 109, depressing the arms 67 and hooks 66 to release the locking dogs 65 from the notched disks 63, and, through the links 52, rocking the pawl carriers 51 and causing the pawls 50, by engagement with the ratchets 49, to bring another set of polishing elements (this time the daubers) into operative position with their lugs 37 in engagement with the yokes 38 on the rods 34. Further angular movement of the gear 1 causes the above named instrumentalities to return the locking dogs 65 into engagement with their co-operating locking disks 63, to remove the locking member 127 from the corresponding hub 290, and to return the pinion 11 into mesh with the gear 8, causing the reciprocation of the rods 34 to be resumed. These operations are repeated until all of the sets of polishing elements have been successively brought into operative position and reciprocated by the rods 34, thereby by completing the cycle of operations of the machine.

Ratchet wheel 70 which controls the electric circuit breaker receives one impulse during each complete revolution of the gear wheel 1 and a sufficient number of teeth are provided on this ratchet wheel so that when the polishing operation has been completed it has made one complete revolution which results in connecting rod 74 being drawn back to open the electric switch 75 thereby stopping the machine. Hand lever 91 is then actuated, which shifts the polishing

sets away from the foot rests, whereupon 65 the shoes may be withdrawn.

I claim as my invention:—

1. In a shoe polishing machine, a foot rest adapted to support a shoe to be polished, a rotatable set of polishing members mounted adjacent said foot rest, selective means to reciprocate one of the polishing members in contact with the shoe and means to rotate the polishing set upon cessation of the reciprocatory motion thereby to bring the 75 other polishing members into successive operating position.

2. In a shoe polishing machine, a foot rest adapted to support a shoe to be polished, a rotatable polishing set comprising a plurality of polishing members mounted adjacent said foot rest, a reciprocating rod adapted to impart motion to one of the said members, means to rotate the polishing set to bring the other polishing members into 85 successive operative relation with the reciprocating rod.

3. In a shoe polishing machine, a foot rest adapted to support a shoe to be polished, a rotatable polishing set including a plurality 90 of polishing members mounted adjacent said foot rest, a reciprocating rod adapted to impart motion to one of the said polishing members, means to rotate the polishing set to bring another polishing member into operative relation with the reciprocating rod, and means to maintain the reciprocating rod in a stationary and central position while the polishing set is being rotated.

4. In a shoe polishing machine, a foot rest 100 adapted to support a shoe to be polished, a rotatable polishing set mounted adjacent said foot rest, said polishing set including a plurality of slidably mounted brush members, each brush member including a central brush portion secured to a slotted back member, end and top brush portions hinged to said central brush portion, and spring means to press said end and top brush portions into contact with the surface of the 110 shoe to be polished, means to reciprocate said brush members relative to the surface of the shoe to be polished, and means to rotate said polishing set to successively place said brush members in operative position 115 relative to the shoe to be polished.

5. In a shoe polishing machine, a foot rest adapted to support a shoe to be polished, a rotatable polishing set mounted adjacent said foot rest, said polishing set including a plurality of brushes and a combined liquid magazine and dauber having a plurality of compartments so connected one to the other as to conform to the surface of the shoe to be treated when brought 120 into operative relation thereto, means to reciprocate the members of said polishing set upon the surface of the shoe to be

- polished, and means to rotate said polishing set to successively place said brush members in operative position relative to the shoe to be polished.
- 5 6. In a shoe polishing machine, a foot rest adapted to support a shoe to be polished, a polishing set mounted adjacent said foot rest, said polishing set comprising a rotatable brush holder, a plurality of brushes and a combined liquid magazine and dauber slidably mounted on said holder, and means to bring each of said brushes and said dauber into successive operative position relative to the foot rest, and means to reciprocate the respective brush or the dauber while in such position. 70
- 10 7. In a shoe polishing machine, a foot rest adapted to support a shoe to be polished, a polishing set mounted adjacent said foot rest, said polishing set comprising a rotatably mounted holder having a plurality of longitudinal slide bars, a plurality of brushes and a combined liquid container and dauber mounted on said slide bars, said 75
- 15 dauber comprising a plurality of compartments adapted to contain a polishing liquid, spring means secured to the back of said compartments whereby the surface of the dauber is made to conform to the surface of the shoe to be treated and a fluid distributing material secured in the compartments of said dauber, and means to reciprocate the respective brushes or dauber while in position on the surface of the shoe to be 80
- 20 polished. 85
- 25 8. In a shoe polishing machine, a foot rest adapted to support a shoe to be polished, transverse slide rails arranged adjacent said foot rest, a rotatable polishing set mov- 90
- 30 ably mounted on said slide rails, said polishing set including a plurality of slidably mounted brushes and a dauber, means to successively reciprocate said brushes and dauber, springs mounted on said transverse 95
- 35 slide rails to normally maintain the brushes in operative position relative to a shoe to be treated, and means to shift said brushes from operative position. 100
- 40 9. In a shoe polishing machine, a foot rest adapted to support a shoe to be polished, a polishing set arranged adjacent said foot rest, said polishing set comprising trans- 105
- 45 versely slidably supporting brackets, a rotatable brush holder having a plurality of longitudinal slide bars, a plurality of 110
- 50 brushes and a dauber mounted on said slide bars, a reciprocating rod having means adapted to engage the brushes in operative succession, and means operating alternately 115
- 55 to reciprocate said rod and turn said rotatable brush holder. 120
- 60 10. In a shoe polishing machine, a foot rest adapted to support a shoe, a polishing set arranged adjacent said foot rest, said 125
- 65 polishing set including a plurality of brushes and a dauber, means to reciprocate the dauber or one of said brushes, means including a ratchet wheel secured to said brush holder, and a ratchet operating pawls to turn said polishing set and bring said 70
- 70 brushes and dauber into successive operating position. 75
- 75 11. In a shoe polishing machine, a foot rest adapted to support a shoe, a polishing set arranged adjacent said foot rest, said 80
- 80 polishing set including a plurality of brushes and a dauber, means to reciprocate one of said brushes or said dauber, means including a ratchet wheel secured to said brush holder and a ratchet operating pawl to turn 85
- 85 said polishing set and to bring said brushes and dauber into successive operating position, and means to lock said reciprocating rod against movement while said brush holder is being turned. 90
- 90 12. In a shoe polishing machine, a foot rest adapted to support a shoe to be polished, a polishing set arranged adjacent said foot rest, said polishing set including a rotatable brush holder, a plurality of 95
- 95 brushes and a dauber mounted on said holder, means operating alternately to reciprocate the dauber or one of said brushes and to rotate said brush holder, and means to lock said reciprocating means while said 100
- 100 brush holder is being rotated. 105
- 105 13. In a shoe polishing machine, a prime mover, a gear wheel adapted to be driven by said prime mover, a pinion fixed to the shaft of said gear wheel, a pinion mounted 110
- 110 adjacent said gear wheel and adapted to mesh therewith, a gear wheel fixed to said last-named pinion, a square shaft bearing crank arms mounted adjacent said last-named gear wheel, a pinion slidably mounted on said square shaft whereby said shaft is driven, means operated by said first-named gear wheel whereby said sliding pinion is alternately brought into and removed from engagement with the last-named gear wheel, a rotatable polishing set, said polishing set including a plurality of 115
- 115 slidable members, a sliding rod to successively reciprocate said slidable members when in their operative positions, and means connecting the crank arms of said square shaft and said sliding rod whereby said slidable members are reciprocated, and means whereby said polishing set may be rotated to bring said slidable members into successive operating positions. 120
- 120 14. In a shoe polishing machine, a prime mover, a gear wheel adapted to be driven by said prime mover, a pinion fixed to and rotated by said gear wheel, a pinion mounted adjacent said gear wheel and adapted to mesh therewith, a gear wheel af- 125
- 125 fixed to said last-named pinion, a square shaft bearing crank arms and mounted ad- jacent said last-named gear wheel, a pinion 130

- slidably mounted on said square shaft and whereby said shaft is driven, means driven from said first-named gear wheel comprising a pinion, a crank arm, connecting link, 5 lever, and bifurcated elbow lever whereby said slidably mounted pinion is alternately placed in and removed from meshing relation with said second-named gear wheel, polishing sets, each of said polishing sets 10 including a plurality of members, means connected to the crank arms of said square shaft whereby the members are reciprocated in successive order, and means whereby said polishing sets may be rotated to 15 bring said members into successive operating position.
15. In a shoe polishing machine, a prime mover, a gear wheel adapted to be driven by said prime mover, a pinion fixed to and 20 rotated by said gear wheel, a second pinion mounted adjacent said gear wheel and adapted to mesh therewith, a second gear wheel affixed to said last-named pinion, a square shaft having crank arms and mounted adjacent said last-named gear wheel, 25 a pinion slidably mounted on said square shaft adapted to engage said last-named gear wheel whereby said shaft is driven, means comprising a pinion driven from said first-named gear wheel, a crank arm secured to said pinion, a connecting rod, an oscillating lever, a link, and a bifurcated elbow lever whereby said sliding pinion is alternately shifted into and removed 30 from meshing relation with said second-named gear wheel, polishing sets, each of said polishing sets comprising a plurality of members, means connected to the crank arms of said square shaft whereby the members are reciprocated, and means on the 35 opposite side of said first named gear comprising a pinion driven by said first-named gear wheel, a crank arm affixed to said pinion, a connecting rod, an oscillating 40 lever, a link, a rock shaft, a bifurcated lever slidable on said rock shaft, and a ratchet wheel and pawl whereby said polishing set is rotated to bring the members into successive operating position.
- 45 16. In a shoe polishing machine, a prime mover, a gear wheel adapted to be driven by said prime mover, a pinion fixed to the shaft of said gear wheel, a pinion mounted adjacent said gear wheel and adapted to mesh therewith, a gear wheel fixed to 50 said last-named pinion, a square shaft bearing crank arms mounted adjacent said last-named gear wheel, a pinion slidably mounted on said square shaft whereby said shaft is driven, means connected to said first-named gear wheel whereby said sliding pinion is alternately brought into and removed from engagement with the last-named gear wheel, a polishing set, said polishing set including a plurality of slidable 55 members, a sliding rod adapted to reciprocate one of said slidable members, means connecting the crank arms of said square shaft and said sliding rod whereby said slidable members are reciprocated, and 60 means whereby said polishing set may be rotated to bring said members into successive operating positions, and means comprising a lever adapted to be oscillated by said first-named gear wheel and connecting 65 links and a bifurcated locking tongue whereby said reciprocating means are maintained in stationary position while said polishing set is being rotated.
17. In a shoe polishing machine, a foot 70 rest adapted to support a shoe to be polished, said foot rest comprising a standard having a vertical internal channel and a channel on one side face thereof, a rest portion including a dependent spindle adapted to enter said internal channel, a rack member arranged parallel to said dependent spindle, a spiral spring in said internal channel adapted to maintain said rest portion in a relatively elevated position, and spring 75 means acting on said rack bar for maintaining said rest portion in a relatively elevated position, a polishing set arranged adjacent said foot rest, and means to actuate said polishing set.
18. In a shoe polishing machine, a gear 80 wheel, means to rotate said gear wheel, a polishing set of members including a plurality of brushes and a dauber, means connected to and driven by said gear wheel to 85 maintain said rest portion in a relatively elevated position, a polishing set arranged adjacent said foot rest, and means to actuate said polishing set.
19. In a shoe polishing machine, a gear 90 wheel, means to rotate said gear wheel, a polishing set of members including a plurality of brushes and a dauber, means connected to and driven by said gear wheel to 95 maintain said rest portion in a relatively elevated position, a polishing set arranged adjacent said foot rest, and means to actuate said polishing set.
20. In a shoe polishing machine, a foot 100 rest adapted to support a shoe to be polished, a transversely slidably polishing set mounted adjacent said foot rest, means to 105 move said polishing set into and out of operative position with respect to said foot rest, said polishing set comprising supporting brackets, a brush holder rotatably mounted on said supporting brackets, said brush holder having a plurality of longitudinal slide bars, a longitudinally reciprocal rod adapted to serve as an axis for said brush holder, a plurality of brushes and a 110 dauber co-axially arranged with respect to 115
- 160

- said rod, and means carried by said dauber and brushes and said rod whereby said dauber or one of said brush members may be reciprocated.
- 5 21. In a shoe polishing machine, a foot rest adapted to support a shoe to be polished, transversely slidably polishing sets mounted adjacent said foot rest, each of said polishing sets comprising supporting brackets, 10 a brush holder rotatably mounted on said supporting brackets, said brush holder having a plurality of longitudinal slide bars, a longitudinally reciprocal rod adapted to serve as an axis for said brush holder, a plurality of brushes and a dauber co-axially arranged with respect to said rod, means carried by said dauber and brushes and by said rod whereby said dauber or one of said brush members may be reciprocated, 15 and means comprising longitudinally disposed rock shafts arranged adjacent said foot rest and rocker arms whereby said pol- 20
- ishing sets may be shifted from operating position relative to said foot rest.
22. In a shoe polishing machine, a foot rest adapted to support a shoe, a polishing set arranged adjacent said foot rest, said polishing set including a brush holder and a plurality of brushes and a dauber, each brush member and said dauber comprising 25 a plurality of hinged portions, a back member secured to one of said hinged portions, said back member being provided with a lug, a rod adapted to slide in said holder, said rod bearing a yoke adapted to take over the 30 lug on said back member and means to reciprocate said rod.
- In testimony whereof I have hereunto set my hand in presence of two subscribing witnesses.

MARTIN BELVILLE.
